DESIGN FOR A DISPLAY FRAME AND STAND
OR SIMILAR ARTICLE

Maurice J. Schless, New York, N. Y.

Application June 6, 1947, Serial No. 139,498

Term of patent 14 years

(Cl. D80—9)

To all whom it may concern:

Be it known that I, Maurice J. Schless, a citizen of the United States of America and a resident of the city, county, and State of New York, having a post-office address at 2 West 46th Street, New York city, New York, have invented a new, original, and ornamental Design for a Display Frame and Stand or Similar Article, of which the following is a specification, reference being had to the accompanying drawing, forming a part thereof, in which:

Figure 1 is a front elevational view of a display frame and stand or similar article, showing my new design;

Fig. 2 is a side elevational view thereof; and
Fig. 3 is a bottom plan view thereof.

I claim:

The ornamental design for a display frame and stand or similar article, as shown.

MAURICE J. SCHLESS.
